(57) **CLAIM**

The ornamental design for a spool and needle holder, as shown and described.

DESCRIPTION

FIG. 1 is an isometric view of a spool and needle holder showing my new design;

FIG. 2 is a front elevational view thereof;

FIG. 3 is a rear elevational view thereof;

FIG. 4 is a left side elevational view thereof;

FIG. 5 is a right elevational view thereof;

FIG. 6 is a top plan view thereof;

FIG. 7 is a bottom plan view thereof; and,

FIG. 8 is an operational view showing a spool and needle secured to the spool and needle holder.

The broken lines shown in FIGS. 1 and 8 depict environmental subject matter and for no part of the claim. The broken lines shown in FIG. 7 depict portions of the spool and needle holder that form no part of the claim.

1 Claim, 4 Drawing Sheets
